DESIGN FOR A HAIR DRESS COMB OR SIMILAR ARTICLE

Lenora Twomey, New York, N. Y.

Application May 1, 1939, Serial No. 84,701

Term of patent 3½ years

To all whom it may concern:

Be it known that I, Lenora Twomey, a citizen of the United States, residing at 142 West 70th Street, New York, New York, have invented a new, original, and ornamental Design for a Hair Dress Comb or Similar Article, of which the following is a specification, reference being had to the accompanying drawing, forming a part thereof.

Fig. 1 is a perspective view of the front or convex side of a hair dress comb or similar article, showing my new design.

Fig. 2 is a perspective view of the back or concave side of said comb.

Fig. 3 is a top plan view of the comb.

Fig. 4 is a sectional view thereof on the line 4—4 of Fig. 3.

I claim:

The ornamental design for a hair dress comb or similar article, as shown.

LENORA TWOMEY.
